ELECTRONIC COMMUTATOR

Oliver T. Francis, Renville, Minn.

Application June 29, 1939, Serial No. 281,965

18 Claims. (Cl. 179—15)

This invention relates to electronic commutators, and more particularly to a means and method for multiplexing in the transmission and reception of signals.

Various commutators have been used in time division multiplex transmission of signals. These may be summarized as follows:

1. Mechanical commutators consisting of rotary contacts. Such systems present difficulties in synchronism at high speeds, lack flexibility, and therefore permit only a very limited number of channels on a given frequency.

2. Cathode ray tube commutators, consisting of rotating a cathode ray so that it will strike a plurality of anode targets in a predetermined sequence. Such systems require extensive phasing and deflecting apparatus, necessitate the use of high voltages and require amplifying circuits for each of said targets before applied signals are strong enough to be utilized.

3. Thermionic tube commutators, consisting of complicated circuits, whereby signals from one channel render the other channels inoperative. Such circuits are unstable. The number of tubes required for the performance of commutation increases in such circuits as the square of the number of channels.

None of these methods are suited for radio net transmission whereby a single station may transmit to any one of a plurality of geographically separated stations, each of said plurality operating on a different channel due to the complexity and lack of flexibility of said methods.

It is an object of this invention to illustrate a method of multiplexing which shall include a minimum of equipment, which shall be free from the objectionable features of existing systems as outlined above.

Another object is to illustrate a method of communication whereby a single synchronizing transmitting station may be utilized to maintain synchronism between any desired number of transmitting and receiving stations.

Another object is to illustrate a method whereby a carrier frequency may be multiplexed to carry a plurality of voice and telegraph signals.

Another object is to illustrate a method of communication relatively free from atmospheric disturbances which shall consist of scanning a plurality of receiving units in synchronism with said transmitting units, of producing a current of said frequency in each of said receiving units corresponding to currents of said frequency flowing in said transmitting units, of selectively amplifying said current of said frequency in said

receiving units and of translating said amplified current into signals.

In U. S. Patent No. 1,819,599, issued to me August 18, 1931, I illustrated a method of differentially applying a voltage to two grids in a vacuum tube in the path of an electron stream, thereby rendering said tube conductive to only one predetermined magnitude of said voltage. It is an object of this invention to illustrate means whereby the basic principles of said patent may be utilized for scanning a plurality of transmitting and receiving units in synchronism, and of controlling the conductivity of said transmitting and receiving units in accordance with a signal voltage impressed on a third electrode in said electron stream.

Another object is to illustrate a tube having a plurality of grids, means for differentially applying a voltage to two of said grids to render said tube conductive only when said voltage reaches a predetermined value and means for controlling the conductivity of said tube when said voltage reaches said predetermined value in accordance with a signal voltage impressed on a third grid in the path of said electron stream.

Another object is to illustrate a vacuum tube commutator which shall be substantially free from the effects of mechanical and electrical inertia, and capable of performing electrical commutation at any desired speed.

Another object is to provide a commutator wherein the lengths of time to which the units of said commutator responds may be of equal or unequal time length and easily changed from one time length to a longer or shorter period.

Another object is to illustrate a receiver unit in a time division signal system which shall respond to signals only during a period of time when a corresponding transmitting unit may transmit and means for readily adjusting the length of said period at said transmitting and said receiving station.

Another object is to illustrate a selective system, any one of a plurality of electro-responsive devices at a receiving station being operable upon the operation of a corresponding unit at a transmitting station.

Another object is to provide a plurality of channels by multiplexing, and means for further multiplexing each of said channels.

Another object is to provide means for channeling by multiplex, and means for further channeling each of the first channels at a slower speed than said first channels are channelled.

Another object is to provide a negative chan-

nel information system, such as for fire alarms which are operated only in case of a fire.

With these and other objects in view, the invention may be more readily understood by reference to the following description taken in connection with the drawings in which:

Fig. 1 is a transmitting station for sending out synchronizing pulses.

Fig. 2 is a multiplex transmitting station.

Fig. 3 is a receiving station for multiplex signals.

Fig. 4 is another receiving station geographically remote from the station shown in Fig. 3.

Fig. 5 is a synchronizing station similar to Fig. 1.

Fig. 6 is another synchronizing station operating on a frequency different than Fig. 5.

Fig. 7 is a multiplex transmitting station and,

Fig. 8 is a multiplex receiving station for receiving signals sent out by Fig. 7.

The synchronizing station shown in Fig. 1 comprises conventional type of tuned plate tuned grid circuit, consisting of vacuum tube V1, B battery B1, condenser C1, in parallel with inductance L1, feeding antenna AN1, grid condenser C2, grid inductance L2, biasing battery CB1, radio frequency by-pass condenser C3, A battery A1. The output of the transmitter is modulated by a synchronizing pulse generator comprising a neon oscillator N1, supplied with current from battery B2, a variable resistance R1 in parallel with a condenser C4.

The synchronizing pulses from Fig. 1 are picked up at transmitting station Fig. 2 by antenna circuit tuned to 8000 kc, amplified through radio frequency amplifier RFC, and break down three electrode gas discharge device N2. Battery B3 charges condenser C5. The electronic commutator at the transmitting station Fig. 2 comprises vacuum tubes V2, V3, V4, each having an anode, a cathode, and three grids. These grids have been designated as G1, G2, G3, G4, G5, G6, G7, G8, G9, respectively. The grids closest the anodes in these tubes G1, G4, G7 are signal control electrodes. Grid G4 is normally biased past the current cut off by means of CB5. Key K1 shorts resistance R6 and CB5, thereby allowing G4 to assume a zero potential. G7 is similarly biased past the current cut off by CB4. Key K2 shorts CB4 and resistance R7 to permit G7 to attain a zero potential and pass current when K2 is closed. The signal grid G1 of V2 is controlled by voltage variations across R8, in accordance with voltage variations produced by microphone M1 as amplified by vacuum tube V5. CB8 has been placed in the grid circuit of G1 to place the proper operating voltage thereon.

The commutator or scanning grids G2, G3, G5, G6, G8, G9, have been differentially connected through biasing batteries CB2, CB3, in a manner similar to that described in U. S. Patent No. 1,819,599, so that the potential drop across R2, R3 is differentially applied, thereby rendering each of vacuum tubes V2, V3, V4 conductive to one predetermined voltage across R2, R3. Resistances R9, R10, R11, R12, R13, R14 are all high resistances to prevent G2, G3, G5, G6, G8, G9 from assuming a positive potential as the voltages across R2, R3 is varied. In the plate circuit of V2, V3, V4 is B battery B4, and resistance R15. The vacuum tube transmitter V6 is of the conventional tuned plate tuned grid circuit being normally biased to the cut off point by C battery CB9, but sending out signals as current

passes through R15, in response to current through commutator tubes V2, V3, V4. B5 has been connected in the plate circuit of V3 as a means of varying the time V3 is conductive.

At the receiving station Fig. 3, antenna 8000KC picks up synchronized pulse from Fig. 1, which is amplified through RFC and synchronizes the break down of gas discharge device N3 with N2 at the transmitting station Fig. 2 charging condenser C6 in parallel with resistances R16, R17. Commutator tubes V8 and V10 are similar to tubes V2 and V3 at the transmitting station, having signal grids G10 and G13. The commutation grids G11, G12, G14, G15 are similarly connected to biasing batteries CB10, CB11, so as to render V8 and V10 conductive in synchronism with their corresponding commutator units at the transmitting station V2, V3. Resistances R19, R20, R21, R22 prevent these grids from assuming a large positive potential as the voltage across C6 is varied.

The signal grid G10 of V8 is controlled by the voltage drop across R18, in accordance with the signal picked up by antenna 10,000KC, amplified by radio frequency amplifier RFC, C-bias detector V7, in the output circuit of which is plate battery B8 and radio frequency bypass condenser C7. Biasing battery CB15 places the proper voltage upon G10. In the output circuit of V8 is connected anode battery B1 and transformer primary L2. Transformer secondary inductance L3 is connected in parallel with variable condenser C8, so as to be tuned to the synchronizing frequency of N1, which in the present instance may be 20,000 cycles per second. C-bias amplifier detector V9, with C battery CB16, anode battery B9 and electro-responsive device H as plate load is connected so as to amplify current passing through V8 which corresponds to current flowing through commutator unit V2.

Grid G13 of commutator unit V10 which corresponds to unit V3, at the transmitting station is connected through biasing battery CB17 across R18. In the anode circuit of V10 is battery B1 and transformer primary inductance L4. The voltage source B7 is made variable in order that the length of time to which V10 is conductive may be made variable in accordance with the length of time V3 is rendered conductive by varying B5. Transformer secondary inductance L5 in parallel with variable condenser C9 is tuned to the synchronizing frequency of N1, which voltage is amplified by C-bias detector V11, in the grid circuit of which is biasing battery CB14, and in the output circuit of which is battery B10 and signal recorder REC, which may be of any known construction or a synchronizing recorder system such as illustrated in Fig. 8.

Outlying station Fig. 4 is similar to Fig. 3 and is shown merely to illustrate the flexibility of my system of commutation, which renders it applicable for net operation, which is not practicable for existing methods of multiplex. It consists of antenna circuit 8000KC, radio frequency amplifier RFC, gas discharge device N4, and B11, which produces synchronizing voltage across C20 in parallel with resistances R27, R28; commutator unit V20, with synchronizing grids G21, G22, connected through R25, R26, biasing batteries CB20 and CB21, respectively. CB20 and CB21 have been chosen of such value that V20 is conductive only during the time its corresponding commutator unit V4 at the transmitting station is conductive. The signal control grid G20

of V20 is supplied with a signal voltage from antenna 10,000KC amplified through radio frequency amplifier RFC and detected by radio frequency detector DET. If then the synchronizing voltage from N1 is made within the audible range by varying R1, a signal may be heard of synchronizing frequency in electro-responsive device H2, when K2 is closed at the transmitting station.

From a consideration of the principles outlined in U. S. Patent No. 1,819,599 above referred to, it is evident that the commutator units V2, V3, V4 of Fig. 2 are each conductive at one predetermined voltage existing across C5. When N2 breaks down and charges C5 to a high potential, the voltage drop across R3 is sufficient to cancel the effect of the high negative voltage impressed upon G9. The voltage drop across R2 tends to impress a negative potential upon G8 which just cancels the positive potential impressed thereon by CB2. Therefore V4 becomes conductive. Neither V2 or V3 are conductive at this time since the voltage drop across R2 biases G2 and G5 past the current cut off.

As C5 discharges through R2, R3 the voltage drop across R3 becomes just sufficient to cancel the negative potential impressed on G6 by CB3, and the drop across R2 offsets the positive potential impressed upon G5 by CB2. V3 then becomes conductive. Neither V2 or V4 are conductive at this time since CB3 biases G9 past the current cut off of V4, and the voltage drop across R2 biases G2 past the current cut off of V2.

Similarly, when C5 has discharged further CB3 biases V3 and V4 past the current cut off but G2 and G3 assume zero potential and allow V2 to become conductive.

While I have illustrated but three commutator units V2, V3, V4, it is evident that the number is limited only by the accuracy of the synchronizing means. It is not desired to limit my synchronizing means to that illustrated but any synchronizing method utilized in television art for scanning may be used. In this connection it is noted that television screens normally comprise hundreds of thousands of elemental areas, and as such elemental areas in the television screen corresponds to commutator units of Fig. 3, the number of channels possible in my system of multiplex is very large.

In Fig. 7, I have illustrated a means whereby each of the channels shown in Fig. 2 may be further multiplexed, thereby making it possible to use each of the channels of Fig. 2 for teletype or for further additional multiplexed channels.

Referring to Fig. 5, a synchronizing transmitting station is shown. Fig. 5 is composed of transmitter TRAN operating on frequency of 8000 kc., and modulated by M to send out 1000 synchronizing pulses per second. Fig. 6 comprises a transmitter TRAN operating on 6000 kc., and sending out 20 synchronizing pulses per second.

Signal transmitting station Fig. 6, shows gas discharge device N6, which breaks down 1000 times per second in accordance with the synchronizing pulses received from Fig. 5 amplified by RFC. B30 charges C30 in parallel with resistances R30, R31. Vacuum tube V30 corresponding to vacuum tube V3 of Fig. 2 has its commutator grids G30 and G31 connected across R30, R31 through resistances R41, R43 and biasing batteries CB30, CB31, respectively, so as to render commutator tube V30 conductive when C30 has

discharged to a predetermined magnitude of voltage. In the output circuit of V30 is anode battery B34 and load resistance R42 which controls radio transmitter operating on 10,000 kc. The frequencies of transmitters and synchronizing pulses are for illustration only and may of course be varied to meet the requirements.

The control grid G32 of V30 is biased past the current cut off by CB41 and is prevented from ever assuming a high positive voltage by resistance R40. The keying of G32 is effected by a commutator system comprising V31, V32.

The synchronizing pulses of 20 cycles per second sent out by Fig. 6 are picked up by antenna AN2 amplified by RFC and break down gas discharge device N1, permitting B36 to charge condenser C31. The grids G33, G34 of V31 and G31, G38 of V32 have been connected through resistances R44, R60, R46, R48, CB36, CB37 in accordance with the manner previously described for the commutator tubes of Fig. 2, so as to render V31, V32 conductive when C31 has discharged to a predetermined magnitude of voltage. The signal grid G35 is normally biased by CB40 through R45 past the current cut off. When key D, which may be a circuit closed when the letter D is impressed on a teletype machine, removes the negative bias on G35 and allows V31 to become conductive during the portion of the discharge cycle of C31 allotted to V31. Similarly control grid G36 of V32 is normally biased by CB45 through resistance R47 past the current cut off. When key B is closed V32 is similarly rendered conductive. In the output circuit of V31, V32 is connected resistance R38, which controls V30 and permits radio transmitter to send out 1000 cycle pulses as modulated by the 20 cycle pulses of V31, V32.

The receiving station Fig. 8, comprises an antenna AN3 for picking up the 1000 cycle synchronizing pulses from Fig. 5, an amplifier for these pulses RFC to control the breakdown of gas discharge device N8 permitting battery B31 to charge condenser C32. Vacuum tube commutator unit V34 corresponds to V10 of Fig. 3, comprises a plurality of synchronizing grids G39, G40, connected through R50, R51, CB32, CB33 respectively across R32, R33, so that it will pass current only during the period of time that V30 at the transmitting station is conductive. The control electrode G41 of V34 is normally biased past the current cut off by CB43. When a signal from transmitter station Fig. 7 is picked up by AN4, amplified and detected by C-bias detector V31 a positive voltage is impressed across R52 in parallel with C40, which permits V34 to pass current during the period of time that G39 and G40 are at zero potential with respect to the filament.

The recording system comprising antenna AN5 for picking up the 20 cycle synchronizing pulse from Fig. 6, amplifier RFC, gas discharge device N9, which permits B37 to charge condenser C33. Vacuum tube commutator units V35, V36 with synchronizing grids G42, G43, G45, G46 are connected through R53, R54, R55, R56, to proper point on biasing batteries CB34, CB35, so that the voltage drop across R34, R35 will render V35, V36 conductive in synchronism with V31, V32 at the transmitting station. The control grids G52, G44 are connected in parallel. Biasing battery CB44 normally biases these tubes past the current cut off through resistance R57. When however plate current flows in the output circuit of V34 from battery B32 through load resistance R60, the con-

trol grids G52, G44 assume a positive potential, and current flows in the output circuit from B38 through selector magnet D or B when the keys D or B at the transmitting station Fig. 7 are closed.

I have chosen synchronizing stations Fig. 5, Fig. 6 to operate on frequencies different than transmitting station Fig. 7. I am cognizant of the fact that synchronism has been obtained in multiplex system utilizing one of the commutator channels to maintain synchronism. The use of synchronizing transmitters operating on different carriers is believed justifiable in view of the fact that it is contemplated to utilize a large number of signal stations for one carrier, and to utilize the synchronizing pulses for a number of stations operating on different carriers.

As indicated above the number of stations, which it is possible to place on a single carrier is limited only by the accuracy of the synchronizing means. The magnitude of the voltage to which a gas discharge device will charge a condenser, varies somewhat with temperature, the proximity to radio active substances, light, etc. Known methods of magnitude voltage control may be utilized to stabilize this variation, one form of which is shown in Fig. 8, where three element vacuum tube V90, has been placed in parallel with condenser C32. As is well known tubes connected as V90 are highly conductive to currents when the anode voltage impressed thereon exceeds a predetermined value, depending upon the value of the biasing battery CB90, but have a very high resistance to anode voltages below that value. If N8 charges C32 to a higher voltage than said predetermined value, C32 is rapidly discharged to said value, thereby permitting V34 to be operated in synchronism with corresponding transmitting station unit, regardless of variations in the magnitude to which N8 charges C32.

In Fig. 1, I have shown a synchronizing pulse transmitter wherein the frequency of the pulses produced may be varied by variable resistance R1. For the purpose of illustrating the operation of the voice transmission and receiving means comprising V2 and V8 of Figs. 2 and 3, respectively I have assumed in the above specification, this synchronizing frequency to be a supersonic frequency of 20,000 cycles per second. The voice currents from M1 impressed on G1 of V2 modulate the 20,000 cycle pulses, and these modulated pulses in turn modulate the radio frequency waves being transmitted by V6. These double modulated waves are picked up by antenna and RFC circuits associated with V1 and applied to G10 of V8. They are then amplified by the C-bias detector circuit comprising the tube V9 which is connected to the tuned circuit including the secondary of transformer L3, and the condenser C8, tuned to 20,000 cycles per second. This amplification at the synchronizing frequency of 20,000 cycles per second is similar to intermediate frequency amplification so effectively used in amplifier circuits today, whereby the voice frequencies which are superimposed on the intermediate frequency are amplified.

For operation of the siphon recorder, comprising circuits incorporating V3 and V10, this synchronizing frequency has been again assumed to be 20,000 cycles per second. Secondary of L5 and C9 have been tuned to 20,000 cycles for amplification of the synchronizing frequency.

For the operation of the channel incorporating tubes V4 and V20 this synchronizing frequency has been changed to an audible frequency, such as

500 cycles per second, by varying resistance R1, in order to render the signal audible in headphones H2. As previously indicated channel comprising V4—V20 was illustrated merely to 5 show that the system is adaptable to transmission of the International code. Obviously the other two channels comprising V2—V8 and V3—V10, which as previously indicated are tuned to 20,000 cycles per second would be inoperative 10 when channel V4—V20 was operating on 500 cycles, unless these channels were returned to that frequency.

Synchronizing pulse transmitters Fig. 5 and Fig. 6 have been illustrated as sending out pulses 15 of 1000 and 20 cycles per second, respectively. As indicated previously in this specification these transmitters are similar to the one shown in Fig. 1. While 1000 cycles is harmonically related to 20, it is obvious that with separate transmitters 20 of the type shown in Fig. 1, that it would be impossible for the synchronizing frequencies to be controlled so accurately as to maintain a harmonic relation between them and it is not intended to limit their operation to harmonic relationship, all synchronizing frequencies having 25 been chosen for illustration of the operation of the circuit. The advantage of using a plurality of non-interdependent synchronizing voltages is that variations in the frequency of one of said 30 voltages are compensated for by the other. Non-interdependent synchronizing voltages as used in this specification and appended claims, are defined as synchronizing voltages wherein changes 35 in frequencies of one of said voltages due to apparatus imperfections produce no change in the frequency of a second of said synchronizing voltages.

While my electronic commutator has been illustrated in connection with multiplex channeling 40 of carrier frequencies, it is apparent that it may be used in many other ways where high speed commutation is desired without departing from the spirit of the invention. Use in selector systems at once suggest itself, especially in the field 45 of automatic telephony. It is not desired to limit the invention to the forms described above. The invention is to be limited only by prior art and as described in the following claims:

What is claimed is:

1. In a multiplex communication system, a 50 plurality of electronic commutators, each of said commutators comprising a plurality of vacuum tube commutator units, each of said vacuum tubes having a plurality of grids, means for maintaining synchronism between said commutators, said 55 means comprising means for producing a synchronizing voltage, means for applying said voltage to two of the grids in each of said tubes, to tend to produce a positive potential on one of said two grids of each of said vacuum tubes and a negative potential on a second of said two grids of each of said tubes, means for biasing the grids of corresponding units of said commutators to render said corresponding units conductive simultaneously.

2. An electronic commutator, comprising: a 60 plurality of unit vacuum tubes, each of said vacuum tubes having a plurality of grids, means for generating a varying voltage, means for rendering each of said tubes conductive at different magnitudes of said voltage, said last means comprising means for applying said voltage to said grids to tend to produce a positive potential on one of said grids of each of said tubes, and a negative potential on a second of said grids of

each of said tubes, and means for impressing signal energy on a third of said grids in each of said tubes.

3. An electronic commutator, comprising: means for generating a varying voltage, means cyclically operable in succession at different magnitudes of said varying voltage, said generating means comprising a gas discharge device relaxation oscillator, capacitated to start said succession at a predetermined magnitude of voltage depending on the conductive anode to cathode voltage drop of said device.

4. A multiplex system, comprising: a transmitting station, a receiving station, an electronic commutator comprising units cyclically operable in succession at different magnitudes of a varying voltage at each of said stations, means at each of said stations for generating a voltage of predetermined magnitude for starting said succession, said means comprising a source of potential, a resistance and a condenser, and a gas discharge device, said device having an anode and a cathode, the conductive anode to cathode potential drop of said device being substantially independent of current flow, and means for rendering said gas discharge device at each of said stations conductive simultaneously.

5. A multiplex system, comprising: a transmitting station, a receiving station, an electronic commutator at each of said stations, said electronic commutator comprising a plurality of unit vacuum tubes, each having a plurality of grids, means for simultaneously producing a voltage of predetermined magnitude at each of said stations, means for applying said voltage to said grids of said vacuum tubes at each of said stations to tend to produce a positive potential on one of said grids and a negative potential on a second of said grids, means for preventing any of said grids from assuming an excessive positive potential, said last means comprising a separate high resistance in series with each of said grids, means for biasing said grids of said unit vacuum tubes in different magnitudes to render said tubes conductive at different magnitudes of said voltage, and means for varying the magnitude of said voltage produced at each of said stations to render said unit vacuum tubes sequentially operable in synchronism.

6. The method of transmitting signals in multiplex communication with a plurality of groups of channels, which consists in cyclically rendering a first group of said channels operable at a predetermined frequency, controlling a first group of said channels by a second group of channels cyclically operable at a different frequency, controlling said second channels by said signals, and selectively amplifying said signals at said first mentioned frequency.

7. An electronic commutator adapted for multiplex signaling systems and the like, comprising: electronic discharge device means having a plurality of electron current paths, each of said paths having a cathode, an anode and a plurality of control electrodes for controlling the electronic current flow between said cathode and anode, means for applying a varying control potential to selected ones of said control electrodes of each of said paths periodically to periodically vary the sensitivity of each of said electronic commutator paths, the sensitivity of different ones of said paths being maximum for different values of said varying potential, and means for applying signaling energy to another of said control electrodes in each of said paths to modu-

late the electronic current flow of each of said electronic commutator paths.

8. A multiplex signaling system electronic commutator, comprising: a condenser, means for periodically charging said condenser, a discharge circuit connected to said condenser, a multiple grid vacuum tube having a pair of the grids thereof differentially connected to said discharge circuit so that one of said grids is at a positive potential with respect to the cathode of said vacuum tube while the other of said grids is at a negative potential, means for biasing said grids to maintain said vacuum tube substantially non-conductive except when the effects of the potentials on said pair of grids neutralize to permit useful current flow through said vacuum tube, and means for modulating the useful current flowing through said vacuum tube.

9. A multiplex signaling system electronic commutator, comprising: a condenser, means for periodically charging said condenser, a discharge circuit connected to said condenser, a vacuum tube having a cathode, an anode and a plurality of grids, means for differentially connecting a pair of said grids to said discharge circuit so that one of said pair of grids is charged positively with respect to the cathode of said vacuum tube while the other of said pair of grids is charged negatively, means for biasing said pair of grids to permit useful current to flow substantially only when said positive charge neutralizes said negative charge, and means for impressing signal energy on another of said grids to control the useful current flow in said vacuum tube.

10. A multiplex signaling system electronic commutator, comprising: a condenser, means for periodically charging said condenser, a discharge circuit connected to said condenser, a plurality of multiple grid vacuum tubes each having a pair of the grids thereof differentially connected to said discharge circuit to control the useful current flow through each of said tubes, means connected to said discharge circuit and to said pairs of grids of said vacuum tubes to render said vacuum tubes conductive in sequence as said condenser discharges through said discharge circuit, and means for signal modulating said current flowing through each of said tubes.

11. A multiplex signaling system electronic commutator, comprising: a condenser, means for periodically charging said condenser, a discharge circuit connected to said condenser, a plurality of multiple grid vacuum tubes each having a pair of the grids thereof differentially connected to said discharge circuit so that one of said pair of grids is at a positive potential with respect to the cathode of the corresponding vacuum tube while the other of said pair of grids is at a negative potential to permit useful current to flow through each of said vacuum tubes substantially only when the effects of said potentials on said pairs of grids substantially neutralize, means connected to said discharge circuit and to said pairs of grids of said vacuum tubes to render said vacuum tubes conductive in sequence as said condenser discharges through said discharge circuit, and means for impressing a signal on said current flowing through each of said vacuum tubes.

12. A multiplex signaling system electronic commutator, comprising: a condenser, means for periodically charging said condenser, a discharge circuit connected to said condenser, a multiple grid vacuum tube having a pair of the grids thereof differentially connected to said discharge circuit to permit useful current to flow through

said vacuum tube only when the potentials impressed on said differentially connected grids substantially counteract each other to permit an electron current to flow from the cathode to the anode of said vacuum tube, and means for impressing signaling energy on another of said grids to control the current flow through said vacuum tube.

13. In an electrical system, means for generating electrical pulses at desired time intervals, means for producing a voltage, a vacuum tube having a plurality of grids, means for applying said voltage to two grids in said vacuum tube, to tend to produce a positive potential on one of said grids, and a negative potential on a second of said grids, and means for biasing said grids to render said vacuum tube conductive at a desired portion of said time intervals.

14. In a time division system, means for generating electrical voltages at predetermined time intervals, an electronic commutator, comprising a plurality of vacuum tubes each having a plurality of grids, means for applying said voltages to two of said grids in each of said vacuum tubes, to tend to produce a positive potential on a first of said grids of each of said vacuum tubes and a negative potential on a second of said grids of each of said vacuum tubes, and means for biasing the grids of each of said vacuum tubes in different magnitude, to render each of said vacuum tubes conductive at different portions of said time intervals.

15. An electronic commutator, comprising: a plurality of unit vacuum tubes, each of said vacuum tubes having a plurality of grids, means for generating a varying voltage, means for rendering each of said tubes conductive at different magnitudes of said voltage, said last means comprising means for applying said voltage to said grids to tend to produce a positive potential on one of said grids of each of said tubes, and a negative potential on a second of said grids of each of said tubes.

16. The combination with a plurality of electronic commutators, each of said commutators comprising a plurality of commutator unit vacuum tubes, each of said vacuum tubes having a plurality of grids, means for maintaining synchronism between said commutators, said means comprising means for producing a synchronizing voltage, means for applying said voltage to two of the grids in each of said tubes, to tend to produce a positive potential on one of said two grids of each of said vacuum tubes and a negative potential on the other of said two grids of each of said vacuum tubes, and means for biasing the grids of corresponding units of said commutator to render said corresponding units conductive simultaneously.

17. A commutating device comprising: an electronic commutator, comprising a plurality of vac-

uum tubes, each of said vacuum tubes having a plurality of grids, means for generating a varying voltage, means for rendering each of said vacuum tubes conductive at different magnitudes of said voltage, said last means comprising means for applying said voltage to said grids to tend to produce a positive potential on one of said grids of each of said tubes, and a negative potential on a second of said grids of each of said vacuum tubes, means for impressing signal energy on a third of said grids in one of said tubes, said last mentioned means comprising a second electronic commutator comprising a plurality of unit vacuum tubes, each having a plurality of grids, means for generating a second varying voltage, means for rendering each of said tubes of said second commutator conductive at different magnitudes of said second voltage, said last means comprising means for applying said second voltage to said grids of said tubes of said second commutator to tend to produce a positive potential on one of said grids and a negative potential on a second of said grids of said vacuum tubes of said second commutator, means for impressing signal energy on a third of said grids of each of said vacuum tubes of said second commutator, and means for impressing signal energy produced by said second commutator on said third grid of said one of said vacuum tubes of said first commutator.

18. A commutating device comprising: an electronic commutator comprising a plurality of unit vacuum tubes each of said vacuum tubes having a plurality of grids, means for generating a varying voltage, means for rendering each of said tubes conductive at different magnitudes of said voltage, said last means comprising means for applying said voltage to said grids to tend to produce a positive potential on one of said grids of each of said tubes and a negative potential on a second of said grids of each of said tubes, means for impressing signal energy on a third of said grids in each of said tubes, a second electronic commutator comprising a plurality of unit thermionic tubes each having a plurality of control electrodes, means for generating a second varying voltage, means for rendering each of said thermionic tubes conductive at different magnitudes of said second voltage, said last mentioned means comprising means for applying said second voltage to said control electrodes to tend to produce a positive potential on one of said control electrodes of each of said thermionic tubes, and a negative potential on a second of said control electrodes of each of said thermionic tubes, and means for impressing signal energy generated by one of said unit vacuum tubes on a third of said control electrodes in each of said thermionic tubes.
